WEARING-APPAREL STRAP CONSTRUCTION

Joseph Bayon, Angers, France

Application September 11, 1947, Serial No. 773,452
In France January 10, 1947

7 Claims. (Cl. 2—338)

1

It is known to make braces with straps or branches which are tubular, that is to say constituted by a single piece of fabric folded twice in a flat shape and the two edges of which are joined in the middle of the underside, where they are united by a zigzag seam or in another manner. This mode of manufacture has the advantage of avoiding the raveling out of the edges, but it has the drawback that the straps or branches thus formed twist and roll up, particularly at the shoulders of the wearer, so that they bear at these points only on a small width, as a string, causing lack of comfort and even uneasiness to the wearer.

An object of the present invention is to provide a new and improved construction for straps or branches or bands or the like for use in braces, suspenders, garters, belts and the like.

Other objects and advantages of the present invention are apparent in the following detailed description, appended claims and accompanying drawings.

Generally speaking, the present invention contemplates a new and improved construction for a composite strap or band or the like (intended for use in braces, suspenders, garters, belts and similar supporters for wearing-apparel or the like) wherein the strap or band is constructed of two flexible elongated strips of fabric or other appropriate material, each strip having a central longitudinally-extending fold-line to form upper and lower panels; the free edges of the panels of the two strips being disposed in abutting relationship and being interconnected by stitching or other suitable fastening means passing through all of said panels and providing a central stiffening zone in the composite assembled structure.

In one embodiment of the present invention (shown particularly in Figures 3 and 4), the four free edges are cut-edges which are kept from unraveling by the central stitching or seam-line. Since the outer edges of the composite strap are formed by the longitudinal fold-lines, there is no tendency to unravel at said outer edges.

Due to the central reinforcing stitching or seam-line, the composite strap or band of the present invention does not have any appreciable tendency toward twisting.

In a modified embodiment of the present invention (shown in Figure 5), each strap is provided with three longitudinally-extending fold-lines to form a four-ply structure in which the free edges are enclosed and are in juxtaposition to the central fold-line; the two straps being united to each other along the other two fold-

2

lines of each strap (instead of along their free edges).

In this last-mentioned modified embodiment, it is possible, especially when the strips are constructed of light-weight fabric, to reinforce the strips and to render them somewhat softer and more flexible by positioning within the folded-in portions of each strip, either a pair of single-ply insert strips (as shown in Figure 6) or a longitudinally-folded two-ply insert strip fitting across the free edges of the outer strip (as shown in Figure 7).

The accompanying drawing shows by way of example, at an enlarged scale, four embodiments of an article manufactured according to the present method.

Fig. 1 is a front view of a part of a brace branch, during the course of its manufacture.

Fig. 2 is a cross section thereof, in a first embodiment.

Figs. 3 and 4 are similar views of the finished article.

Fig. 5 is a cross section of the finished article, according to a modification.

Fig. 6 is a cross section of the same article, with an internal lining.

Fig. 7 is a cross section showing a modification in the disposition of the internal lining.

On the drawing, 1 and 2 are the two strips which are made, for example, of cloth.

In the first embodiment, each strip is folded together longitudinally, whereafter the two strips are placed side by side (Figs. 1 and 2) so that the cut edges 1a, 1a, 2a, 2a are turned to the interior and that the folded edges 1b, 1b are placed at the exterior. It is then sufficient to unite the four cut edges which are adjacent to each other by a zigzag seam 3, and the article is finished, as shown by Figs. 3 and 4.

In the modification shown by Fig. 5, use is made, for each element which shall have when finished the same width as before, of a strip having the double width, and the upper and lower parts are folded back towards the interior, so that each element then comprises four superimposed layers, and the seam 3 unites the four folded edges 1c, 1c, 2c, 2c which are superimposed two by two and adjacent.

In this embodiment, and when the used fabric or material is light, it may be lined internally, either by four separate strips 4 of flannel or other appropriate material, each of which is placed in an inner fold of each element (Fig. 6), or by two strips 5 folded at 5a and placed astride over the cut edges of the strips 1 and 2.

It will be noticed that the present method

makes it possible to constitute the articles in question by two strips of different color and to obtain thereby, additionally, an original aspect of the article.

It will be understood that the invention is not limited to the embodiments which have been described and shown, and that it will be possible to employ any other appropriate means for uniting the two elements constituting the article. On the other hand, the invention covers also the articles obtained by the present method.

I claim:

1. A band for use in a garment supporter or the like comprising two elongated strips of flexible material each having a generally central longitudinal fold-line providing top and bottom panels, the free edges of the panels being disposed in generally abutting relationship, and fastening means interconnecting the four abutting free edges of said panels, thereby providing a generally central stiffening zone extending longitudinally along said band.

2. A band for use in a garment supporter or the like comprising two elongated strips of flexible material each having a generally central longitudinal fold-line providing top and bottom panels, the free edges of the panels being disposed in generally abutting relationship, and a row of stitching interconnecting said abutting free edges, said stitching passing through the top and bottom panels of each of said strips and providing a central stiffening zone extending longitudinally along said band intermediate said fold-lines.

3. A band for use in a garment supporter or the like comprising two elongated strips of flexible material each having generally parallel cut edges and a generally central longitudinal fold-line providing top and bottom panels, the cut edges of the panels being disposed in generally abutting relationship, and fastening means interconnecting the four abutting cut edges of said panels, thereby preventing unraveling of the cut edges and providing a generally central stiffening zone extending longitudinally along said band.

4. A band for use in a garment supporter or the like comprising two elongated strips of flexible material each having generally parallel cut edges and a generally central longitudinal fold-line providing top and bottom panels, the cut edges of the panels being disposed in generally abutting relationship, and a row of zigzag stitching interconnecting the abutting cut edges, said stitching passing alternately through the top and bottom panels of each strip and serving to prevent unraveling of the cut edges as well as to

provide a central stiffening zone extending longitudinally along said band generally intermediate said fold-lines.

5. A band for use in a garment supporter or the like comprising two elongated strips of flexible material each having a generally central longitudinal fold-line providing top and bottom panels, the free edges of said top and bottom panels being turned inward to provide a generally four-ply construction, the inturned free edges of said two strips being disposed in generally abutting relationship, and a row of stitching passing through all of the four plies of each strip generally adjacent said inturned free edges, said stitching serving to interconnect said strips and also providing a generally central stiffening zone extending intermediate said fold-lines.

6. A band for use in a garment supporter or the like comprising two elongated strips of flexible material each having a generally central longitudinal fold-line providing top and bottom panels, the free edges of said top and bottom panels being turned inward to provide a generally four-ply construction, a lining-strip underlying the top and bottom panels of each of said first-mentioned strips, and a row of stitching interconnecting the abutting free edges of said panels and providing a generally central stiffening zone extending intermediate said fold-lines.

7. A band for use in a garment supporter or the like comprising two elongated strips of flexible material each having a generally central longitudinal fold-line providing top and bottom panels, the free edges of said top and bottom panels being turned inward to provide a generally four-ply construction, a lining-strip disposed within each of said first-mentioned strips, each lining-strip having a generally central fold-line disposed in juxtaposition to the fold-line of the outer strip and providing top and bottom panels underlying the top and bottom panels of the outer strip, and a row of stitching interconnecting the free edges of said first-mentioned strips and providing a stiffening zone extending generally centrally along said band.

JOSEPH BAYON.
